UNITED STATES PATENT OFFICE.

VICTOR BEAUREGARD, OF BOSTON, MASSACHUSETTS, ASSIGNOR OF ONE-HALF TO CHARLES S. GOODING, OF BROOKLINE, MASSACHUSETTS.

DOOR CHECK AND SPRING.

SPECIFICATION forming part of Letters Patent No. 651,098, dated June 5, 1900.

Application filed May 29, 1899. Serial No. 718,745. (No model.)

To all whom it may concern:

Be it known that I, VICTOR BEAUREGARD, a citizen of the United States, residing at Boston, in the county of Suffolk and State of Massachusetts, have invented new and useful Improvements in Door Checks and Springs, of which the following is a specification.

This invention relates to that class or type of pneumatic door checks and springs where-
10 in a cylinder is pivotally connected at one end and contains a piston having a piston-rod connected through intermediate devices with the door and by intermeshing gear with a spring contained within a barrel or casing.
15 In prior door-checks of this character the gears must turn on their pivot-bearings or spindles, and the spring is connected by such gears to the piston-rod, the construction being complicated, expensive, unreliable, and
20 unsatisfactory in use, and, further, is such that in operation considerable lateral or side pressure is brought to bear upon the piston-rod and piston, thus creating objectionable friction and rapidly wearing the piston-packing and in heavy doors, where comparatively powerful or strong springs are required, caus-
25 ing so much friction from the lateral or side pressure referred to as to render the device practically inoperative, due to excessive friction.

The chief objects of my invention are to improve, simplify, and render more economical the character of door checks and springs referred to and to provide a novel construction wherein the spring has no direct working connection with the piston-rod, whereby friction on the piston and piston-rod is reduced to the minimum without regard to the power or strength of the spring required and
35 the door check and spring are rendered more easy, effective, reliable, and satisfactory in practical operation and can be used on either a right or left hand door.

To accomplish these objects, my invention involves the features of construction, the combination or arrangement of parts, and the principles of operation hereinafter described and claimed, reference being made to the accompanying drawings, in which—

50 Figure 1 is a plan view of my improved

door-check, showing the same attached to a door and door-casing in the position assumed by the check when the door is closed. Fig. 2 is a similar view showing the position assumed by the check when the door is opened 55 part way or to an angle of nearly ninety degrees, the cylinder being broken away and shown partly in section. Fig. 3 is a front elevation of my improved check attached to a door and door-casing. Fig. 4 is a detached 60 front elevation of the spring-casing, bracket, and cylinder-holder with the cylinder removed and the piston-rod in section. Fig. 5 is a vertical sectional elevation on line 5 5, Fig. 1. Fig. 6 is a horizontal section through 65 the cylinder and spring-casing, taken on the line 6 6, Fig. 4. Fig. 7 is an elevation of a modified form of bracket.

In the drawings, 1 is a pneumatic cylinder having a cap 2 soldered or brazed thereon, a 70 screw 3 tapped into the cap 2, and a washer 4 to regulate the size of the opening through which the air is expelled from the cylinder when the door is closing, as hereinafter set forth. An adjustable link 5 is pivoted at one 75 end, at 6, to the cap 2 and at the other end, at 7, to the bracket 8, said bracket 8 being shown fastened by screws 9 to the door-casing 10. The cylinder 1 is screw-threaded at 11 and is screwed into a hole at 12, tapped 80 into the cylindrical boss 13, formed upon the holder 14. Said holder 14 has a cylindrical projection 15 formed upon its under side and constructed with a bore or hole 16, whereby the projection is adapted to fit and turn 85 freely upon the vertical hollow bearing 17 of the cylindrical spring-casing 18. Said bearing 17 is cylindrical upon its outside and has a square hole 19 extending vertically and longitudinally through said bearing to receive a 90 square pin or stud 20, formed upon or attached to supporting-bracket 21, said bracket being shown fastened by screws 22 to the door 23. The spring-casing 18 is held stationary upon the bracket 21 by the square 95 stud 20. Said casing has gear-teeth 24 cast upon its outer surface or perimeter, said gear meshing the rack 25, cut in the piston-rod 26.

It will be evident that the cylinder 1, cap 2, and holder 14 constitute a movable connect- 100

ing-link between the adjustable swing-link 5 on the door-frame and the supporting-bracket 21 on the door, and since the spring-casing 18 and its gear-teeth 24 are constantly held 5 in a stationary position with relation to the supporting-bracket there will be no increase of friction on the piston and piston-rod in the operation of the device, as there is no actual working connection of the spring in the casing with the piston and piston-rod, and the piston-rod travels in a circular path around the fixed gear. In practice it has been demonstrated that by this construction and operation the piston and piston-rod are constantly 10 free from lateral or side pressure and friction.

15 A piston 27, consisting of a metal disk 28 and leather washer 29, is fastened to the piston-rod by the nut 30. When the piston 27 is drawn back in the cylinder 1 to its full 20 throw, as shown in Fig. 6, the gear 24 and rack 25 are cut away on the pitch-line in the ordinary manner of constructing intermittent gearing, so that any farther opening of the door will not move the piston in the cylinder. 25 A flat helical spring 31 is inclosed in the spring-casing 18, one end bearing against or fast to the casing and the other end turned in to engage one of the slots 32 in the cylindrical projection 15 upon the cylinder-holder 30 14. The tension of the spring can be regulated by placing the end in different slots 32.

35 It is evident that instead of a flat helical spring a torsional spiral spring of wire could be employed to perform the same function as the flat spring, and in this case the tension on the spring could be varied by placing one end thereof in holes drilled in the top of the holder 14 at distances apart corresponding to the slots 32.

40 A washer 33 and split pin 34 serve to hold the spring-casing and other parts upon the stud 20.

The operation of the device is as follows: 45 As the door is opened from the position shown in Fig. 1 to that shown in Fig. 2 the piston is caused to travel lengthwise of the cylinder 1 on account of the relative change in the position of the cylinder 1 and cylinder-holder 14 in relation to the door and to the gear 24, 50 it being understood that the gear bears at all times a fixed position upon the bracket 21. When the door is closing, the piston will be moved in the opposite direction in the cylinder and the air compressed, checking the door 55 and preventing slamming. By screwing up on the regulating-screw 3 the time required for the compressed air to escape from the cylinder 1 as the door is closing may be increased and the door caused to close very slowly, and 60 vice versa.

It will be seen that by placing the gear-teeth upon the outside of the spring-casing 18 the following advantages are secured: First, the teeth of the gear 24 can be cast without adding to the expense of the spring-casing; second, the gear-teeth being placed outside the casing secure the quick opening of the pis-

ton when the door is first opened—a feature which is essential in a pneumatic check, and, third, the cylinder is practically at right angles to the door when the latter is near its closing-point, and thus the greatest checking efficiency is secured.

70 It will be noted that the cylindrical boss 13 is so arranged in relation to the rest of the cylinder-holder 14 that when the parts of the device are assembled the center line of the cylinder 1 is midway between the top and bottom of the spring-casing 18. The object of this construction is to adapt the check for 75 use on a right or left hand door and on the hinge side or on the side opposite thereto.

In the drawings I have shown the check applied to a right-hand door on the hinge side. To adapt the check for use on a left-hand door on the hinge side, the only change necessary would be to remove the split pin 34 and washer 33, lift the check off the square stud 20, invert it, replace it on the stud 20, and replace the split pin and washer. This 80 can be done without wrench, screw-driver, or other tools. To adapt the check for use upon doors on the side opposite the hinges, I provide a bracket 35, Fig. 7, and screw it to the under side of the casing. The bracket 8 is 85 secured to the door instead of the casing, and the check is placed in the reverse position to that which it would occupy upon the hinge side of the same door. It will thus be seen that without taking the check apart it can be 90 placed upon the bracket 8 or upon the bracket 35, so as to fit a right or left hand door and inside or outside of said doors, as may be desired. This is a very important and valuable feature of my invention, as it enables 95 the check to be sold by the hardware trade for any door by inclosing both brackets 8 and 35 with the check.

100 It is evident that the piston 27 and piston-rod 26 might be removed and the device used as a reversible door-closing mechanism, or the spiral spring 31 might be removed and the device used as a door-checking mechanism without departing from the spirit of my invention.

105 It will be seen and understood that there is absolutely no side strain upon the piston and piston-rod when the door is being checked, thus eliminating friction and wear upon said parts and also upon the cylinder 1. The 110 checking strain is transmitted through the piston and piston-rod to the fixed spring-casing through the gear-teeth upon said piston-rod and casing.

115 It will be seen that the herein-described 120 check does not require accuracy or nicety either in its construction or in setting it up and that the wearing parts would last for a great many years, with the exception of the leather washer 29, which can be easily replaced when worn out by unscrewing the cylinder 1 from the holder 14, unscrewing the 125 nut 30 from the piston-rod 26, and replacing the worn-out washer with a new one, when

the check will be as good as new. This can be performed by any one without the use of tools and at a merely nominal expense.

Having thus described my invention, what I claim, and desire to secure by Letters Patent, is—

1. In a pneumatic door-check, a pneumatic cylinder, one end pivotally connected to a supporting-bracket adapted to be attached to a door or door-casing, the other end pivotally connected to a link adapted to be attached to a door-casing or door, in combination with a piston, a piston-rod constructed with a rack along its length, and a gear held constantly

15 stationary with relation to said supporting-bracket during the action of the check and directly engaging the rack on the piston-rod.

2. In a pneumatic door-check, a pneumatic cylinder one end pivotally connected to a supporting-bracket adapted to be attached to a door or door-casing, the other end pivotally connected to a link adapted to be attached to a door-casing or door, in combination with a piston, a piston-rod constructed with a rack 25 along its length, and a gear held stationary with relation to said supporting-bracket, intermittently engaging directly with said rack, and about the center of which the rack travels.

3. In a pneumatic door-check, a pneumatic cylinder, one end pivotally connected to a supporting-bracket adapted to be attached to a door or door-casing, the other end pivotally connected to a link adapted to be attached to a door-casing or door, in combination with a piston, a piston-rod provided with a rack, a spring-casing constructed externally with a gear extending partially around its circumference and meshing with the rack, and means 35 for holding the said spring-casing and gear 40 in a fixed position on said bracket during the operation of the check.

4. In a pneumatic door-check, the combination of a supporting-bracket, a spring-casing constructed externally with a gear, a spring in the casing, means for holding said casing constantly in a stationary position on said bracket, a cylinder, a link pivoted to one end of the cylinder, and a piston having a piston-rod constructed along its length with 45 a rack meshing with and adapted to travel around the stationary gear of said spring-casing as the door opens and closes.

5. In a pneumatic door-check, a pneumatic cylinder, one end pivotally connected to a link, said link adapted to be pivotally connected to a door-casing or door, the other end of said cylinder pivotally connected to a bracket adapted to be attached to a door or door-casing, a piston and piston-rod, a rack 55 fast to said piston-rod, and a non-rotatable gear meshing said rack in combination with a spring, one end of said spring connected

with the cylinder, the other with the bracket to which said cylinder is pivoted.

6. A reversible door-closing mechanism, 65 comprising in its construction a pair of links pivoted together, one of said links adapted to be pivotally connected to a door-casing or door, the second link pivoted to a reversible spring-casing, a spring one end connected to 70 said spring-casing, and the other end to said second link, and a bracket on which said spring-casing is detachably and reversibly mounted, substantially as described for the purpose specified. 75

7. A reversible door checking and closing mechanism comprising in its construction a pneumatic cylinder, one end pivotally connected to a link, said link adapted to be pivotally connected to a door-casing or door, the 80 other end of said cylinder fast to a holder pivotally connected to a spring-casing, a spring one end connected to said holder and the other end to said casing, a piston and piston-rod, mechanism for moving said piston 85 in said cylinder, and a bracket adapted to be attached to a door or door-casing and on which said spring-casing is detachably and reversibly mounted.

8. A reversible door checking and closing 90 mechanism, comprising in its construction a pneumatic cylinder, one end pivotally connected to a link, said link adapted to be pivotally connected to a door-casing or door, the other end of said cylinder fast to a holder 95 pivotally connected to a spring-casing, a spring one end connected to said holder and the other end to said casing, a piston and piston-rod, a rack extending along the length of said piston-rod, a non-rotatable gear meshing 100 said rack, and a bracket on which said spring-casing is detachably and reversibly mounted.

9. A pneumatic door-check, comprising in its construction a pneumatic cylinder, one 105 end pivotally connected to a link adapted to be pivotally connected to a door-casing or door, the other end of said cylinder fast to a holder 14 pivotally connected to a spring-casing 18, so constructed and arranged that the 110 center line of the pneumatic cylinder is in a horizontal plane substantially midway between the top and bottom of said spring-casing, and a supporting-bracket on which said spring-casing is detachably and reversibly 115 mounted, substantially as described for the purpose specified.

In testimony whereof I have hereunto set my hand in presence of two subscribing witnesses.

VICTOR BEAUREGARD.
